(57) **CLAIM**

The ornamental design for a personal watercraft, as shown and described.

DESCRIPTION

FIG. 1 is a perspective view showing our new design; FIG. 2 is a right side elevational view thereof; FIG. 3 is a top plan view thereof; FIG. 4 is a front elevational view thereof; FIG. 5 is a rear elevational view thereof; and, FIG. 6 is a left side elevational view thereof. The broken line showing of environmental structure in FIGS. 1-6 is for illustrative purposes only and forms no part of the claimed design.
